[57] CLAIM

The ornamental design for stand for an ornament or plate, substantially as shown and described.

DESCRIPTION

FIG. 1 is a perspective view of a stand for an ornament or plate showing my new design;

FIG. 2 is a right side elevational view thereof;

FIG. 3 is a top plan view thereof;

FIG. 4 is a front elevational view thereof; and

FIG. 5 is a rear elevational view thereof;

FIG. 6 is a perspective view of a stand for an ornament or plate showing a second embodiment of my new design;

FIG. 7 is a front elevational view thereof; and

FIG. 8 is a right side elevational view thereof;

FIG. 9 is a perspective view of a stand for an ornament or plate showing a third embodiment of my new design;

FIG. 10 is a front elevational view thereof; and

FIG. 11 is a right side elevational view thereof.
